[57] **CLAIM**

The ornamental design for a bird feeder, as shown and
described.

DESCRIPTION

FIG. 1 is a front elevational view of a bird feeder showing
the new design, with the rear view being a mirror image
thereof;

FIG. 2 is a top plan view thereof;

FIG. 3 is a left side elevational view thereof, with the right
side being a mirror image thereof;

FIG. 4 is a left side perspective thereof;

FIG. 5 is a bottom plan view thereof; and,

FIG. 6 is a left side perspective view thereof, illustrating its
use with a bird feeder stand not considered part of the bird
feeder.

The bird feeder stand in FIG. 6 is shown in broken lines for
illustrative purposes only and forms no part of the claimed
design.
